UNITED STATES PATENT OFFICE.

WILLIAM HALE DRIGGS, OF WASHINGTON, DISTRICT OF COLUMBIA,
ASSIGNOR TO THE DRIGGS-SEABURY ORDNANCE CORPORATION,
OF SHARON, PENNSYLVANIA, A CORPORATION OF PENNSYLVANIA.

SEMI-AUTOMATIC GUN.

No. 805,272.

Specification of Letters Patent.

Patented Nov. 21, 1905.

Application filed April 10, 1905. Serial No. 254,827.

To all whom it may concern:

Be it known that I, WILLIAM HALE DRIGGS, a citizen of the United States, residing at Washington, in the District of Columbia, have invented certain new and useful Improvements in Semi-Automatic Guns; and I do hereby declare the following to be a full, clear, and exact description of the invention, such as will enable others skilled in the art to which it applies to make and use the same.

My invention relates to improvements in semi-automatic guns, or those guns in which it is intended to open the breech either automatically or by hand, to load by hand, and to close the breech either automatically or by hand.

The invention, as shown in the drawings, is embodied in the gun of the Hotchkiss type, in which there is a vertically-reciprocating breech-block, although features of the invention may be embodied in guns of other than this well-known Hotchkiss type.

Reference is had to the accompanying drawings, in which the same parts are indicated by the same letters throughout the several views.

Figure 1 is a side elevation of the gun and shoulder-bar, parts being broken away. Fig. 2 is a plan view of the parts shown in Fig. 1. In both of these figures the gun and shoulder-bar are shown; but the cradle and other parts of the gun-mount are omitted, these not being a part of my present invention. Fig. 2^a is a detail showing a plan view of the cam-piece and contiguous parts on a larger scale than is indicated in Fig. 2; parts being shown in dotted lines. Fig. 3 is a rear view of the device shown in Figs. 1 to 2, parts being shown in section. Fig. 4 is a detail showing the hub of the hand-lever for operating the breech mechanism by hand or automatically. Fig. 5 is a perspective view of the extractor. Fig. 6 is a perspective view of the pivoted operating-cam. Fig. 7 is a side elevation showing the hand-lever and the firing mechanism. Fig. 8 shows a side view of the trigger and sear and illustrates the operation of the firing mechanism. Fig. 9 shows the means for connecting the pivoted operating-cam to the shoulder-bar. Fig. 10 is a section on the line 10-10 of Fig. 9 looking in the direction of the arrows and illustrates the means provided for throwing the operating-cam out of the operative position, so that the gun may be

worked entirely by hand, if desired; and Fig. 11 is a diagram showing the engagement of the extractor with the breech-block when the breech-block is in the open position and illustrates the method of automatically releasing the breech-block when a fresh cartridge-case is inserted.

A represents the body of the gun, provided with the usual housing for the breech-block.

B represents the shoulder-bar, which is connected to the cradle (not shown) in any suitable way.

C represents the breech-block, which is provided with the usual cam-groove C' for the lug on the crank and also with the groove C^o for the lug on the extractor and with the step c^o to engage said lug, as will be hereinafter described.

D represents the hand-lever, which is provided with the ordinary handle D' and with an enlarged hub D^o, which hub slips over the square shaft E, journaled in the body of the gun, and the said hub is locked to the said shaft by a tongue f, projecting from the spring F into a recess d^o through the walls of the opening D^o for the shaft E. (See Fig. 4.)

G represents the operating-crank, which is fast to the shaft E and is provided with an operating-lug G'. This lug G' is flattened somewhat on top, as at g, to afford a better holding-surface to prevent the gun from being prematurely opened by any jar; but this is a well-known expedient.

H' represents a shaft journaled in the block and having rigidly attached thereto the cocking-toe H, the hammer H^o having the firing-point h and the toe H^o, which engages the lug k on the block K, fast to the rod K', which rod carries a button K^o, adapted to compress the firing-spring K^o when the firing mechanism is cocked. The firing mechanism is normally held in the cocked position by means of a sear M, pivoted, as at m, in the breech-block and provided with a catch m', engaging a corresponding catch k' on the hub H^o, which hub is fast to the shaft H'. This sear carries at its downward lower end a pin m^o, which engages in an elongated slot n in the sliding block N, which is dovetailed, as at n^o, into a groove e^o in the breech-block. This block N terminates in a nose n^o, which normally bears against the arm O, fast to the shaft O', which shaft carries the trigger O^o. This shaft O' is

held in place by a spring-keeper O^3 , which may be lifted and the shaft withdrawn when desired, as for convenience in dismounting. A spring M^6 presses on the back of the sear, as shown in Fig. 8, and normally holds the trigger in the forward position; but when the trigger is pulled backward, the sliding block N presses the sear out of engagement with the hub H^4 and allows the spring K^3 to throw the hammer forward about the shaft H' , thus firing the gun.

The extractor P is provided with guide-ribs p , which slide in corresponding guideways in the housing at one side of the breech-block, and the extractor has a nib or claw P' , which engages the rim of the cartridge-case. The extractor also is provided with the lug P^2 , which is preferably rounded, as at p^3 , on its forward face and is flattened, as at p^2 , on its lower face. This lug P^2 slides in the groove C^0 , and as the breech-block is lowered the rounded edge p^3 of the lug strikes the cam-face c^0 of the groove C^0 and pushes the extractor backward until the flat face p^2 rests above the shoulder c^0 , the block being lowered slightly farther than is otherwise necessary in the operation of the gun. As the block is raised either under the automatic or hand operation, this lower face of the lug P^2 will arrest the upward movement of the block until a cartridge-case is put in, when the rim of the cartridge-case engaging the extractor will slide it slightly forward, disengaging the face p^2 of the lug P^2 and the shoulder c^0 of the groove C^0 , at which time the breech-block is free to be operated either automatically or by hand.

Having thus described the hand operation of the gun, I will now show how the breech 40 may be opened or closed automatically.

The hand-lever D is provided with a hook D^6 and with the cam-lug D^6 . A chain Q is connected to a rod Q' , passing through the coil-spring Q^2 , and terminates in a screw-threaded end q , carrying a nut q' and a washer q^2 , by means of which the compression on the spring Q^2 may be adjusted within limits. The rear end of this spring bears against a shoulder on the shoulder-bar; but in practice 50 the spring will ordinarily be mounted in the casing, and this casing is fitted in a recess in the shoulder-bar.

R represents the pivoted operating-cam, having the cam-block R' with the inclined 55 yielding surface r' and the engaging surface r' . This block R is pivoted to the shoulder-bar, as shown in Figs. 6, 9, and 10, in which T represents a pin having a lug t , which projects into the recess between the shoulders r^2 and r^3 at one side of the pivot-hole r^0 in the block R . This block R when the gun is to be used as a semi-automatic gun is normally, pressed inward about a pivot by means of the spring R^2 , so that when the gun recoils the 65 face d^6 of the cam-lug D^6 will strike the in-

clined face r and will press the block R backward against the action of the spring, thus allowing the lug D^6 to pass by; but on counter-recoil the face d^6 on the cam-lug D^6 will strike the face r' on the cam-lug R' , and the block R not yielding when in this position will cause the cam-lug D^6 to rock the operating-lever D backward, thus opening the breech. As the breech-block is lowered the extractor will be cammed backward until the lug P^2 passes above the shoulder c^0 , and as the breech starts to close again when the gun nears the initial position the spring Q^2 , which has been compressed during recoil, will swing the breech-block far enough upward to cause the shoulder c^0 to engage the face p^2 of the lug P^2 on the extractor and the breech-block will be arrested against further upward motion until the fresh cartridge-case is inserted, when the extractor will be dragged forward, 85 releasing the breech-block and allowing it to continue its upward movement to the closed position. This operation is illustrated most clearly in Figs. 7 and 11.

In order to throw the semi-automatic attachment out of operation, it will only be necessary to swing the resilient arm T' on the pin T until the point t^2 beneath the handle t' engages in the notch b^3 in the shoulder-bar. This will rock the block R inward about its pivot sufficiently far to prevent the cam-lug R' from striking the cam-lug D^6 , so that the gun may move freely on recoil and on counter-recoil without affecting the automatic attachments in any way.

It will be noted that when the automatic attachment is in engagement, that when the face d^6 of the cam-lug D^6 engages the face r' on the cam-lug R' , there will be a tendency not to wedge the block R outward against its spring, but to swing it inward about its pivot, thus securing a firm engagement. To prevent this block from being swung in too far, I provide a lip r^4 , which strikes a shoulder on the shoulder-bar, and thus limits the inward swing of the cam-piece R .

It will be obvious that various modifications might be made in the herein-described apparatus which could be used without departing from the spirit of my invention.

Having thus described my invention, what I claim, and desire to secure by Letters Patent of the United States, is:

1. In a gun, the combination with the gun-body, and the cradle in which said gun-body recoils, of an operating-lever carried by the gun-body, and breech mechanism operated thereby, a cam-lug on said lever, a swinging cam-piece having a cam on the inner side thereof, projecting inward toward the axis of the gun, and lying in a vertical plane between the pivot of said cam-piece and the axis of the gun, a vertical pivot-pin locked to said cam-piece and pivoted in said cradle, forming the pivot for said cam-piece, a resilient arm se- 130

cured to said pivot-pin, and provided with a catch at its free end, for holding said pivot-pin and the cam-piece locked thereto in the desired position, and a spring normally tending to press the free end of said cam-piece inward against the action of said arm, substantially as described.

2. In a gun, the combination with the gun-body, and the cradle in which said gun-body recoils, of an operating-lever carried by the gun-body, and breech mechanism operated thereby, a cam-lug on said lever, a swinging cam-piece having a cam on the inner side thereof, projecting inward toward the axis of the gun, and lying in a vertical plane between the pivot of said cam-piece and the axis of the gun, a vertical pivot-pin locked to said cam-piece and pivoted in said cradle, forming the pivot for said cam-piece, a resilient arm secured to said pivot-pin, and provided with a catch at its free end, for holding said pivot-pin and the cam-piece locked thereto in the desired position, and a spring normally tending to press the free end of said cam-piece inward against the action of said arm, and a sliding extractor locking the breech-block in the open position until engaged by the rim of the cartridge-case in the operation of loading, substantially as described.

In testimony whereof I affix my signature in presence of two witnesses.

WILLIAM HALE DRIGGS.
